CLAIM

The ornamental design for a baby diaper changing station cover, as described.

DESCRIPTION

FIG. 1 is a front plan view showing my new design of a baby diaper changing station cover.

FIG. 2 is a right side view of the baby diaper changing station cover in a stored position.

FIG. 3 is a right side view of the baby diaper changing station cover in a use position.

FIG. 4 is a left side view of the baby diaper changing station cover in the stored position.

FIG. 5 is a right side view of the baby diaper changing station cover in the use position.

FIG. 6 is a top front right perspective view of the baby diaper changing station cover in the use position.

FIG. 7 is a top front left perspective view of the baby diaper changing station cover in the use position.

FIG. 8 is a top front right perspective view of the baby diaper changing station cover in the stored position.

FIG. 9 is a top front left perspective view of the baby diaper changing station cover in the stored position; and,

FIG. 10 is a top back right perspective view of the baby diaper changing station cover in the use position.

The dash double dash broken lines in the drawings indicated the boundary of the claimed design. The broken line showing of the baby changing station indicates the environment of the claimed design, and the remaining broken lines are portions of the baby diaper changing station cover. None of the broken lines form part of the claimed design.

Features not shown in the drawings form no part of the claimed design.
